SCREW-ROTOR COMPRESSORS OR MOTORS

John Rutger Munck af Rosenschöld, Saltsjöbaden, and Sven Ivar Trulsson, Nacka, Sweden, assignors to Atlas Copco Aktiebolag, Nacka, Sweden, a corporation of Sweden

Filed Apr. 16, 1958, Ser. No. 728,861

Claims priority, application Sweden Apr. 17, 1957

3 Claims. (Cl. 62—331)

This invention relates to screw-rotor compressors or motors operating on an elastic working fluid and comprising a casing and two or more screw-type rotors mounted in bearings in said casing and intermeshing to form working chambers for said working fluid which working chambers move from registry with an inlet port at the casing in which one fluid pressure prevails to register with an outlet port at the casing in which another fluid pressure prevails, as the rotors revolve. Machines of the above type are most commonly used as compressors but may also be operated as motors. For the sake of simplicity, the following detailed description of apparatus embodying the invention describes such apparatus only when used as a compressor, which fact, however, should not be considered as a limitation of the scope of the invention as set forth in the claims.

In apparatus of the kind under consideration, for small pressure differences, i.e. less than 2 kilogrammes per square centimetre, it has been possible to use ball bearings for the mounting of the rotor shafts and it has also been possible to arrange the rotors in the casing in any convenient manner. In such compressors operating with a pressure difference in excess of 2 kgs./sq.cm. between the inlet and the outlet of the compressor it has been common practice to use only plain bearings for the rotor shafts since the bearing loads have been considered too high for ball or roller bearings at the speeds at which said compressors are normally operated. Compressors of the kind under consideration have the disadvantage that they produce an intense and irritating noise. Such compressors have, further, the disadvantage that the efficiency drops very quickly if the clearance between the rotors and between the rotors and the casing is larger than absolutely necessary. One object of this invention is to reduce the above mentioned deficiencies and to provide a compressor which emits as little disturbing noise as possible in the room where the compressor is mounted and which simultaneously shows a good efficiency and has small bearing loads.

By locating the rotor shafts in a common horizontal plane with the port communicating with the working chambers in which the high pressure prevails disposed at the underside of the rotors and with the port communicating with the working chambers in which the low pressure prevails disposed at the upper side of the rotors the pressure difference between the upper and the under sides thereof during operation of the compressor or motor helps to lift the rotors and the weight of the rotors is consequently partially compensated for, so that a portion of the radial pressure on the radial bearings of the rotor shafts is counterbalanced by fluid pressure. The provision of radial roller bearings for the rotor shafts makes it possible to reduce the clearance between the rotors and between the rotors and the casing to a very small value so that leakage through the machine is reduced to a minimum and the efficiency is increased which is also a result of the reduced bearing loads and of the reduction of the frictional resistance produced thereby.

2

The invention has, furthermore, the advantage that the casing enclosing the rotors may be divided horizontally along the common rotor shaft plane so that the upper half of the casing may be removed for inspection without moving other parts of the machine or of the pipe connections. The provision of noise-emitting pipes and conduits below the floor of the room in which the compressor or motor is mounted reduces the disturbing noise in said room materially so that the noise in said room is on an acceptable level and, furthermore, the forces originating from the system of pipes and conduits is transmitted directly to the foundation of the compressor or motor without stressing the compressor or motor casing. By providing the opening in which the high pressure prevails at the underside of the casing, said casing may without inconvenience be provided with stiffening ribs or the like at the portion which has the greatest load. Conduits to an intermediate cooler of a compressor which may preferably be disposed below the floor level may in accordance with the invention be made with reduced length which also helps to maintain good efficiency and to reduce the disturbing noise.

The above and other detailed objects of the invention and the advantages to be derived from its use will appear as the ensuing portion of this specification proceeds.

In the accompanying drawings one embodiment of a compressor plant and a screw compressor embodying the invention is illustrated by way of example.

Fig. 1 is a side view and partial section of a compressor plant embodying the invention. Fig. 2 is an end view of the plant according to Fig. 1. Fig. 3 is a longitudinal section through one of the screw compressors shown in Figs. 1 and 2. Fig. 4 is a plan view of the compressor shown in Fig. 3. Fig. 5 is a section on line V—V in Fig. 3, and Fig. 6 is a section on line VI—VI in Fig. 3.

The compressor plant illustrated in Figs. 1 and 2 consists of a low-pressure compressor 1, a high-pressure compressor 2 and an electric motor 3 which drives the compressors. The motor and the compressors are mounted in a machine room on a concrete foundation 4. The compressors 1 and 2 are essentially of the same design and in order to disclose the invention the high pressure compressor 2 only is described in detail. Said compressor consists of a casing which comprises a lower portion 5 and an upper portion 6 providing two horizontally extending intersecting bores for the reception of the rotors, a two-piece intake end closure structure 7, 8, and an end closure structure 9 at the outlet end. Air is supplied to the compressor 2 through a conduit 10 which at the opening 11 is connected to the underside of the casing portion 7, 8, and the air compressed in the compressor 2 is discharged from the compressor through a pipe 12 which at the opening 13 is connected to the underside of the compressor casing portion 5. In the compressor casing two screw-type rotors 14 and 15 are mounted with their shafts in radial roller bearings 16 and 17, respectively, with the shafts disposed in a single horizontal plane 31. The rotors are, furthermore, provided with plain thrust bearings 18 at one end to take care of the axial forces. From the opening 11 the passage 19 in the inlet end closure structure 7, 8 leads to an inlet port 20 at one end of the upper end portion of the bores in which the rotors are situated and from an outlet port 21 at the lower end portion of the bores in which the rotors are situated a passage 22 runs from the underside of the rotors to the pipe 12 and further through an aftercooler 23 to a pipe line 24. From the drawings it will be evident that the inlet and outlet ports may be said to be disposed, respectively, at the diagonally opposite upper and lower end portions of the bores in the casing. Air from the atmosphere is admitted at 25 and conducted through a

pipe 26, an admission valve 27 and a pipe 28 to the low-pressure compressor 1. From the low-pressure compressor the air is conducted through a pipe 29 and an intermediate cooler 30 to the pipe 10 and the high-pressure compressor 2 as described hereinabove. All pipes and coolers are disposed below the floor 32 of the machine room.

The compressor described hereinabove and illustrated on the accompanying drawings should be considered only as an example and the details of the invention may be modified in several different ways within the scope of the claims. In order to unload the rotors from axial pressure the rotors of the high- and low-pressure stage may, for instance, be connected. The invention may, as stated in the preamble of this specification, also be employed in screw motors which are driven by compressed air or hot gas. The invention may naturally be used in connection with two- or multiple-stage compressors as well as in single-stage compressors.

What we claim is:

1. A rotary device of the character described for operation with an elastic fluid working medium comprising a casing having two horizontally extending intersecting bores and closure structure at the ends of said bores and said casing further having a low pressure port and a high pressure port located, respectively, at the diagonally opposite upper and lower end portions of said bores, two screw-type rotors mounted for rotation in said bores and intermeshing to form working chambers for said working medium, which chambers register with different ones of said ports in different positions of rotation of the rotors and progressively decrease in length toward the high pressure port as the rotors revolve, said rotors having shafts located in a common horizontal plane in said casing, radial roller bearings mounted in said closure structure for supporting said rotor shafts in said casing, a first passage for low pressure working medium extending from a first opening on the underside of said casing to said low pressure port, and a second passage for high pressure working medium extending from said high pressure port to a second opening on the underside of said casing.

2. A device as defined in claim 1, in which said first

passage comprises two branches extending respectively on opposite sides of the mountings for said bearings to connect said first opening with said low pressure port.

3. A rotary compressor plant of the character described for compressing an elastic fluid working medium comprising a floor structure, a foundation structure, a compressor casing having two horizontally extending intersecting bores and closure structure at the ends of said bores and said casing further having a low pressure inlet port and a high pressure outlet port located, respectively, at the diagonally opposite upper and lower end portions of said bores, two screw-type rotors mounted for rotation in said bores and intermeshing to form working chambers for said working medium, which chambers register with different ones of said ports in different positions of rotation of said rotors and progressively decrease in length toward the high pressure port as the rotors revolve, said rotors having shafts located in a common horizontal plane in said casing, radial roller bearings mounted in said closure structure for supporting said rotor shafts in said casing, a first passage for low pressure working medium extending from a first opening on the underside of the casing to said low pressure inlet port, a second passage for high pressure working fluid extending from said high pressure port to a second opening on the underside of said casing, a cooler mounted in said foundation structure, a fluid intake passage in said foundation structure, a first conduit disposed substantially in said foundation structure and leading from said intake passage to said first passage in the casing, a second conduit disposed substantially in said foundation structure and leading to said cooler from said second passage in said casing, and means carried by said foundation structure and disposed substantially above the level of said floor structure for driving said rotors.
